UNITED STATES PATENT OFFICE.

EMANUEL F. BERGREEN, OF BROOKLYN, NEW YORK.

SHOW-CASE BRACKET.

1,144,930.

Specification of Letters Patent. Patented June 29, 1915.

Application filed August 14, 1914. Serial No. 856,828.

To all whom it may concern:

Be it known that I, EMANUEL F. BERGREEN, a citizen of the United States, residing at Brooklyn, in the county of Kings and State of New York, have invented certain new and useful Improvements in Show-Case Brackets; and I do hereby declare the following to be a full, clear, and exact description of the invention, such as will enable others skilled in the art to which it appertains to make and use the same.

This invention relates to new and useful improvements in show case brackets, and has for its principal object to provide a device which will permit the top of the show case to be swung upwardly in order to allow free access to the interior.

Another object of the invention is to provide a simple and effective means for holding the glass of the show case and preventing it from becoming displaced.

With these and other objects in view, the invention consists in the novel combination and arrangement of parts which will be fully set forth in the following specification and accompanying drawings, in which,

Figure 1 is a front view in elevation of a bracket constructed in accordance with this invention, Fig. 2 is a sectional view taken on line 2—2 of Fig. 1, Fig. 3 is a top plan view of a fragment of a show case constructed in accordance with this invention, Fig. 4 is a sectional view of a modified form of show case bracket showing the same in its raised position, Fig. 5 is an enlarged detail sectional view thereof, Fig. 6 is an enlarged horizontal sectional view of one of the brackets, the central or intermediate bracket, and Fig. 7 is a view similar to Fig. 6 of one of the end brackets.

Referring now to the drawings by characters of reference, the numeral 1 designates as an entirety a show case constructed in accordance with this invention. This show case comprises the base 2 which is supported in any suitable manner and has secured thereto the upstanding arms 3, which are provided at their lower terminals with the angular extensions 4. These extensions are provided with screw-receiving apertures through which the screws 5 are arranged to extend, and it will be clearly seen that in this manner the brackets may be firmly secured in place. Formed in the sides of the upstanding portions 3 are the grooves

6 in which the plates 7 are held. These grooves 6 are of sufficient distance apart to permit the glass plates, forming the walls of the show case 8, to be placed between the plates 7 hereinbefore referred to.

Extending angularly from the upper extremity of the upstanding member 3 is the arm 9 which tapers at its free end and is braced by means of the filler member 10 as clearly shown in Fig. 2. The outer corner of the upstanding portion is provided with a pair of spaced ears 11 having formed therein a central aperture 12 through which the pivot pin 13 is arranged to extend.

A pair of arms 14 having formed thereon the ears 15, is provided and these ears are provided with alining apertures through which the pivot pin 13, hereinbefore referred to, is arranged to extend. Secured to the upper surfaces of the arms 14 are the plates 16 which are of the same width as the arms 14 and are arranged to coöperate therewith in holding the glass in place. Each of these arms is rabbeted along its upper and outer edge as at 17 and this rabbeted portion is arranged to receive the glass 18 forming the upper wall of the show case. A downturned extension 19 is formed at the end of each of the plates 16, and these downturned ends are bent inwardly as at 20 and arranged to overlie the end of the arm 9 as clearly shown in Fig. 2.

In Fig. 7 the upstanding member is only provided on one side with a single groove in which the plate 21, which is bent angularly as at 22 along its outer edge, is arranged to rest. This plate is arranged to partially overlie the surface of the glass 23 to hold the same firmly in place, and prevent any displacement thereof. These brackets are used only at the ends of the show case and are so arranged as to leave a finished surface at the end thereof.

It will be apparent from the foregoing that in use when it is desired to open the case, the flange 20 is released from its position beneath the end of the arm 9 and the glass swung upwardly on the pivot 13, thus allowing the user free access to the interior of the case. In order to properly support the device at the desired angle, the bars 9 are provided on their upper surfaces with suitable notches in which the pivoted arm 24, which may be secured to the members 14, is arranged to rest. It will thus be seen that the glass top of the show case may be sup-

ported at any desired angle, thus permitting the user to easily and quickly gain access to the interior of the show case and eliminate any danger of the device being accidentally closed.

With the use of this device it is evident that a show case of any number of sections may be constructed and the device will remain at all times closed.

10 While in the foregoing there has been shown and described the preferred embodiment of this invention, it is to be understood that such changes may be made in the combination and arrangement of parts as will fall within the spirit and scope of the invention as defined in the appended claims.

What is claimed is:

1. A show case bracket including an up-
20 standing member, an arm formed at the up-
per terminal of the upstanding member, a
pair of bars pivotally secured to the up-
standing member and arranged to lie parallel
25 with the arm, each of said bars being
rabbeted along their outer edges, and a plate
overlying the bars and overhanging the rab-
beted portion, thereby forming a groove to
receive the glass forming the walls of the
show case.

2. A show case bracket comprising an up-
30 right, an arm formed at the upper end of
the upright, a pair of ears projecting from
the upright on the side opposite the arm,

bars pivotally secured to the ears, said arms
being arranged to lie in parallel relation to
the arms and being rabbeted on their outer
35 edges, and plates secured to the bars, said
plates overhanging the rabbeted portions to
form grooves in which the top plate of the
show case is arranged to be held.

3. The combination with a base, a bracket
secured to the base, said bracket comprising
an upstanding member, an angular exten-
sion at the lower terminal of the upstanding
member, said extension being provided with
40 screw holes arranged to receive screws by
means of which the device is secured to the
base plate, an inwardly extending arm at
the upper terminal of the upstanding mem-
ber, ears projecting in the opposite direc-
45 tion of the arm, a pivot pin extending
through the ears, a pair of bars pivotally
mounted on the pivot pin, each of said bars
being rabbeted on its outer edge, and plates
secured to the upper surface of the bars, said
50 plates being arranged to overlie the top
thereof and overhang the rabbeted portions
to hold a glass in place, and means to hold
the bars normally downwardly.

In testimony whereof I affix my signature
in presence of two witnesses.

EMANUEL F. BERGREEN.
